COMBINED PRIMARY CONTROL AND IGNITER FOR OIL BURNER

Frederick T. Bauer, Holland, Mich., assignor to
Robertshaw Controls Company, Richmond, Va.

Filed Jan. 13, 1975, Ser. No. 540,688

Term of patent 14 years

Int. Cl. D23—03

U.S. Cl. D23—126

FIG. 1 is a reduced perspective view of a combined primary control and igniter for oil burner showing my new design;

FIG. 2 is a top plan view thereof;
FIG. 3 is a bottom plan view thereof;
FIG. 4 is a front elevational view thereof;
FIG. 5 is a rear elevational view thereof;
FIG. 6 is a side elevational view taken from the left of FIG. 1; and

FIG. 7 is a side elevational view taken from the right of FIG. 1.

I claim:

The ornamental design for a combined primary control and igniter for oil burner, as shown.
